CLAIM

The ornamental design for a “portable chair and backpack,” as shown and described.

DESCRIPTION

FIG. 1 is a perspective view of a portable chair and backpack in a collapsed, backpack configuration, showing my new design;

FIG. 2 is a perspective view thereof, illustrating the portable chair and backpack in an open, chair configuration;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
